UNITED STATES PATENT OFFICE.

CHARLES F. WALTERS, OF RICHMOND, INDIANA, ASSIGNEE TO THE RICHMOND CITY MILL WORKS.

FRICITION ATTACHMENT FOR FLOUR PACKERS.

SPECIFICATION forming part of Letters Patent No. 320,419, dated June 16, 1885.

Application filed May 6, 1885. (No model.)

To all whom it may concern:

Be it known that I, CHARLES F. WALTERS, a citizen of the United States, residing at Richmond, in the county of Wayne and State of Indiana, have invented certain new and useful Improvements in Friction Attachments for Flour-Packers; and I do hereby declare the following to be a full, clear, and exact description of the invention, such as will enable others skilled in the art to which it appertains to make and use the same.

My invention relates to that class of flour-packers used in packing flour in barrels and sacks.

15 My invention consists in the mechanical devices, hereinafter described and claimed, for producing an adjustable automatic friction attachment, by means of which an increased or decreased pressure may be communicated to 20 the packer and a uniform pressure of any degree be maintained.

In the drawings, Figure 1 is a side elevation of my improvement, showing the spring-case in transverse vertical section. Fig. 2 is a side 25 elevation of the same. Fig. 3 is an elevation of the spring-case, with hand-lever attached by which the case and its attachments are raised or depressed. Fig. 4 is a rear elevation of the same, showing the manner of attaching the case to the hand-lever and their 30 relative positions.

In Fig. 1, *a a* represent upright posts, connected near the top by a cross-framing, *x*, upon which rests a horizontal shaft, *b*, journaled in the cross-framing *x*, on the outer end of which is placed a pulley-wheel, *c*, which is rigidly fixed to the shaft *b*. A belt, *d*, is applied to the upper circumference of the wheel *c*, one end of which is secured to a rod, *e'*, the upper portion 40 of which is made flat and is secured to the end of the belt *d*, while the lower portion, passing through an opening in a horizontal ledge formed upon a bracket, *e*, is furnished with a screw-thread and thumb-nut, *g*, the latter having 45 its bearing against the lower edge of the ledge *f* of the bracket *e*, by means of which the belt *d* is made adjustable with reference to the bracket *e*, which is rigidly attached to the post *a*. The other end of the belt *d* is attached to 50 a hinged lever, *h*, by suitable means at a point

below the wheel *c* nearly perpendicular to its center. The lever *h* is pivoted to the post *a* at *j*, so that the opposite end is permitted a vertical motion, and near its outer end it is furnished with projections *v v*, having holes *i*, 55 into which is hooked a vertical rod, *l*, which passes through a spherical case, *n*, and a coiled spring, *r*, which is confined in said case. The lower portion of the rod *l* is furnished with a screw-thread, with a thumb-nut, *m*, above the 60 case and a similar thumb-nut, *m'*, below the case, by which the case carrying the spring can be moved vertically upon the rod *l*. A hand-lever, *o*, is attached to the rear surface of the spring-case *n*, as seen at Fig. 4, and is 65 hinged to the post *a* at *s*, and is permitted at its outer end a vertical motion, and carrying with it the case *n*. The nut *m'* rests against the lower surface of a collar, *y*, upon which the coiled spring *r* has its bearing, and the 70 pressure exerted by the rod *l* is communicated to the spring *r* and is met by its resistance. When the friction belt is placed on the periphery of the pulley-wheel *c*, and the end secured at the bracket *e*, the opposite end being 75 attached to the lever *h*, as described, the rod *l* is connected with the lever *h*, the spring-case and lever *o* being attached. It will be seen that as the lever *o* is depressed from a horizontal to a vertical position a compound leverage is 80 exerted upon the friction belt, enforcing its contact and tractile force upon the face of the wheel *c*, which extends over the largest part of its circumference, and which strain or pressure is rendered uniform and continuous 85 by the action of the spring *r*, which takes up any stretching or expansion of the friction-belt *d* and equalizes the strain. The spherical case *n* is provided with a projection, *n'*, of fan shape, with a depending lip, as seen at *n'*, and 90 an opening of a corresponding form is made in the lever *o*, which allows the lever to pass on to the projection when it is in a horizontal position, and which retains it in place when turned down.

95 It will be seen that my improved friction attachment is capable of adjustment separately and independently, first, by the thumb-nut *g* on the bracket *e*; second, by the holes *i* in the projections of the lever *h*; third, by 100

thumb-nuts m m' on the rod l , as well as by the general result of the depression to a vertical position of the lever o .

Having thus fully described my invention, 5 what I claim as new, and desire to secure by Letters Patent, is—

1. The hinged lever h , provided with the projections, v v , having holes i , combined with the belt d and rod l , as and for the purposes herein 10 described.

2. The case n , provided with projection n' , in combination with rod l , collar y , spring r ,

nuts m m' , and lever o , substantially in the manner and for the purposes herein described.

3. The combination of the wheel c , belt d , 15 constructed as described, lever h , rod l , case n , spring r , and lever o , as and for the purposes set forth.

In testimony whereof I affix my signature in presence of two witnesses.

CHARLES F. WALTERS.
